RAILWAY SIGNALING SYSTEM

George R. Pflasterer, Swissvale, Pa., assignor to
The Union Switch & Signal Company, Swiss-
vale, Pa., a corporation of Pennsylvania

Application June 5, 1937, Serial No. 146,599

21 Claims. (Cl. 246—46)

My invention relates to railway signaling systems of the type involving light signals which are approach lighted. Specifically, my invention relates to signaling of the type described wherein the signals involved include at least two lamps and wherein the filaments of both lamps of a signal are checked as to continuity while such lamps are extinguished as well as while such lamps are lighted.

10 The apparatus provided by this invention is an improvement on the systems shown and claimed in the applications of Henry S. Young, Serial Nos. 245,716 and 245,717, filed December 14, 1938, for Railway signaling system.

15 I shall describe several forms of railway signaling systems embodying my invention, and shall then point out the novel features thereof in claims.

20 In the accompanying drawings, Figs. 1A, 1B, 20 and 1C are diagrammatic views which, when placed end to end in the order named, illustrate one form of apparatus embodying my invention. Fig. 2 is a diagrammatic view illustrating a modification of a portion of the apparatus shown in Fig. 1A, and also embodying my invention.

25 Similar reference characters refer to similar parts in each of the several views.

30 Referring first to Figs. 1A, 1B, and 1C, the reference characters R1 and R2 designate the rails of a stretch of railway track over which traffic normally moves in the direction indicated by the arrows. The rails R1 and R2 are divided, by insulated joints 9, into a plurality of sections V—W, W—X, X—Y, and Y—Z. Each section is further divided, as here shown, into two subsections 35 1T, 2T, 3T, 4T, etc. Each subsection is provided with a track battery 10 connected across the rails at one end of the subsection and with a track relay, designated by the reference character TR with a prefix the same as the prefix in the 40 reference character of the associated subsection, connected across the rails at the other end of the subsection.

45 Located adjacent the entrance end of each track section is a signal each designated by a suitable distinguishing reference character and each including an upper indication unit U and a lower indication unit L. Each indication unit, as here shown, is of the type commonly known as a searchlight signal. Referring to signal 12, for example, the units of that signal each comprise an armature 16 mounted to rotate between an intermediate position to which it is biased, and two extreme positions. Each armature 16 is controlled by an armature winding 17, and is polarized by the field from a permanent magnet or an electromagnet (not shown) in such manner that when the winding 17 is energized, the armature will rotate to its left-hand or right-hand extreme position according as winding 17 is then

supplied with current of normal or reverse polarity, respectively. Attached to each armature 16 to rotate therewith are three colored roundels G, R, and Y, which are arranged to be disposed in the path of a beam of light projected from an associated lamp UE or LE according as the armature 16 occupies its left-hand extreme position, its intermediate position, or its right-hand extreme position, respectively. For convenience in illustration, each lamp UE and LE in the drawings is shown disposed above the associated roundels, but it will be readily understood that in actual practice each lamp will be located directly back of the associated roundel and will have associated therewith a suitable optical system, not shown, for projecting a beam of light from the lamp. Operatively connected with each armature 16 is a circuit controller comprising two movable contact fingers 18 and 19. The movable contact finger 18 cooperates with a fixed contact 20 to close a contact 18—20 when the armature 16 occupies its left-hand extreme position, and with a fixed contact 21 to close a contact 18—21 when the armature occupies its intermediate position or its right-hand extreme position; while the movable contact finger 19 cooperates with a fixed contact 22 to close a contact 19—22 when the armature occupies its right-hand extreme position, and with a fixed contact 23 to close a contact 19—23 when the armature occupies its intermediate or its left-hand extreme position. A signal of the type described is disclosed and claimed in Letters Patent of the United States No. 1,864,224, granted to Wesley B. Wells, on June 21, 1932, for Light signal.

35 For governing the signals, each section is provided with two line circuits each including a pair of conductors extending to the signal for the section next in advance and each including front contacts of the associated track relays.

40 For governing the lamps UE and LE of the signals, each section is provided with an approach lighting relay designated by the reference character ER with a prefix the same as the reference character of the associated signal. The lamps UE and LE are controlled in such a manner as to become lighted whenever the associated relay ER is released, and the relays ER are controlled in such a manner as to become released whenever the section next in rear of the associated section 45 becomes occupied.

45 Each section is provided with a suitable source of direct current and with a suitable source of alternating current, the terminals of which are designated by the reference characters B and C, 55 and BX and CX, respectively.

50 For governing the character of the current supplied to the lamps UE and LE, each section is provided with a power-off relay designated by the reference character PO with a prefix the same as 60

the reference character of the associated signal. That is, the current for the energization of the lamps UE and LE is supplied from the associated terminals BX and CX or from the associated terminals B and C according as the associated relay PO is energized or deenergized, respectively. The relays PO are governed in such a manner as to be energized only when the source of alternating current is present. The current for lighting the lamps, therefore, is normally supplied from the alternating current source but is automatically switched over to the direct current source when the alternating current is absent.

For governing the polarity of the current supplied to the line circuits for the section next in rear, each section is provided with two pole changing relays designated by the reference characters UPC and LPC each with a prefix the same as the reference character of the associated signal.

For controlling the relays PC and the current supplied to the line circuits for the section next in rear as well as for governing both mechanisms of the associated signal, each section is provided with an auxiliary lightout relay designated by the reference character LOP with a prefix the same as the reference character of the associated signal.

For at times controlling the relays LOP, each section is provided with two direct current light-out relays designated by the reference characters ULO and LLO each with a prefix the same as the reference character of the associated signal. Each relay ULO and LLO is connected in series with the lamps UE and LE, respectively, of the associated signal whenever the associated approach lighting relay ER is released. Since relays ULO and LLO are direct current relays, I have connected across the winding of relays ULO and LLO asymmetric units 24 and 24A for the purpose of by-passing each half wave of alternating current so that the relays will operate on alternating current. It will be apparent, therefore, that each relay ULO and LLO will become energized whenever the lamps UE and LE, respectively, of the associated signal are lighted either by alternating current or by direct current.

Each auxiliary relay LOP is provided with two energizing circuits. Referring to signal 14, for example, relay 14LOP is normally energized by a circuit which passes from terminal B through front point of contact 25 of relay 14ER, filament 26 of lamp UE of signal 14, wire 27, filament 28 of lamp LE of signal 14, front point of contact 29 of relay 14ER, back point of contact 30 of relay 14ULO, back point of contact 31 of relay LLO, and relay 14LOP to terminal C. When relays 14ULO and 14LLO are both energized, however, relay 14LOP is provided with another energizing circuit which passes from terminal B over front contact 32 of relay 14ULO, front point of contact 34 of relay 14LLO, and relay 14LOP to terminal C. Relay 14LOP, therefore, is energized only if the filaments of each lamp UE and LE are intact both when the lamps are extinguished as well as when the lamps are lighted. It is understood, of course, that the resistance of relay 14LOP is of such value that the current required by this relay will not be sufficient to light lamp filaments 26 and 28 when connected in series therewith.

Each relay LOP is provided with control circuits similar to those just described for the relay 14LOP.

Associated with each section is a full wave

rectifier designated by the reference character Q with a prefix the same as the reference character of the associated signal. Each rectifier Q has its input terminals connected across the lower line conductors for the associated signal and its output terminals, of course, supply energy in one direction only regardless of the direction of energization of the associated pair of line conductors. As will be described more in detail hereinafter, the rectifiers Q are effective, at times, when the associated relay LOP is released, to supply energy in the reverse direction to each winding 17 of the associated signal to cause both mechanisms to assume the condition for the display of a yellow light.

Associated with each upper indication unit U is a clear repeating relay and a caution repeating relay designated by the reference characters DP and HP, respectively, each with a prefix the same as the reference character of the associated signal. The relays DP and HP are energized when the associated indication unit U is energized in the normal and reverse directions, respectively. For example, relay 11DP is energized by a circuit which includes contact 18-20 of upper unit U of signal 11, and relay 12HP is energized by a circuit which includes contacts 18-21 and 19-22 of upper unit U of signal 12. Each of the other relays DP and HP is controlled in a similar manner.

Having thus described in general the apparatus shown in Figs. 1A, 1B, and 1C, I shall now describe the operation of the system.

Each of the signals is capable of displaying the following indications: When windings 17 of the upper and lower mechanisms are both deenergized (see signal 15), that signal is caused to assume a condition for the display of a red light over a red light to indicate "stop" when relay 15ER becomes released. The lighting circuit for lamp UE may be traced from terminal BX through front point of contact 33 of relay 15PO, relay 15ULO and asymmetric unit 24 in multiple, back point of contact 34 of relay 15ER, filament 26 of lamp UE, back contact 35 of relay 15ER, and front point of contact 36 of relay 15PO to terminal CX. The lighting circuit for lamp LE may be traced from terminal BX through front point of contact 33 of relay 15PO, relay 15LLO and asymmetric unit 24A in multiple, back point of contact 37 of relay 15ER, filament 28 of lamp LE, back contact 35 of relay 15ER, and front point of contact 36 of relay 15PO to terminal CX.

The lamps UE and LE for each of the other signals are provided with lighting circuits similar to those just traced for the lamps associated with signal 15.

When the upper mechanism U is energized in the reverse direction and the lower mechanism L is deenergized (see signal 14), the signal is in condition to display a yellow light over a red light to indicate "approach" when associated lamps UE and LE become lighted.

When the upper mechanism U is energized in the reverse direction and the lower mechanism L is also energized in the reverse direction (see signal 13), the signal is in condition to display a yellow light over a yellow light to indicate "approach medium" when associated lamps UE and LE become lighted.

When the upper mechanism U is energized in the reverse direction and the lower mechanism L is energized in the normal direction (see signal 12), the signal is in condition to display

a yellow light above a green light to indicate "approach intermediate" when associated lamps UE and LE become lighted.

- When upper mechanism U is energized in the 5 normal direction and lower mechanism L is de-energized (see signal 11), the signal is in condition to display a green light above a red light to indicate "proceed" when its lamps UE and LE are lighted.
- 10 As here shown, a train K occupies the section immediately to the right of location Z so that signal 15 is in the "stop" condition. As a result, winding 17 of upper mechanism U of signal 14 is energized in the reverse direction and winding 17 of lower mechanism L of that signal is deenergized. The circuit for winding 17 of upper unit U may be traced over a path from terminal B at signal 15 through relay 15ER, back point of contact 40 of relay 15UPC, front contact 41 15 of relay 8TR, front contact 42 of relay 7TR, front point of contact 43 of relay 14LOP, winding 17, front point of contact 44 of relay 14LOP, front contact 45 of relay 7TR, front contact 46 of relay 8TR, and back point of contact 47 of relay 15UPC 25 to terminal C.

Since signal 14 is in condition to display the "approach" indication, winding 17 of upper unit U of signal 13 is also energized in the reverse direction over an easily traced circuit which includes the upper line conductors of section X-Y and which is similar to the circuit just traced for winding 17 of unit U of signal 14. The positioning of unit U of both signals 13 and 14 in the extreme right-hand position will cause both 30 relays 13HP and 14HP to be energized over easily traced circuits similar to the circuit already traced for relay 12HP. Since relays 14HP and 13HP are both energized, a circuit is established for energizing winding 17 of lower unit L of signal 13 in the reverse direction, which circuit may be traced over a path from terminal B at signal 14 through front contact 50 of relay 14LOP, front contact 51 of relay 14HP, back point of contact 52 of relay 14LPC, front contact 53 of 40 relay 6TR, front contact 54 of relay 5TR, front point of contact 55 of relay 13LOP, winding 17, front point of contact 56 of relay 13LOP, back contact 57 of relay 13DP, front contact 58 of relay 13HP, front contact 59 of relay 5TR, front contact 60 of relay 6TR, and back point of contact 61 of relay 14LPC to terminal C.

Since signal 13 is in condition to display the "approach medium" indication, relay 13UPC will remain released but relay 13LPC and the lower 55 line conductors for section W-X will both become energized. The circuit for relay 13LPC may be traced over a path from terminal B through front contact 62 of relay 13LOP, contacts 18-21 and 19-22 of lower unit L of signal 13 and relay 60 13LPC to terminal C.

With the apparatus at signal 13 in this condition, winding 17 of upper unit U of signal 12 remains energized in the reverse direction over an easily traced circuit but winding 17 of the 65 lower unit L of signal 12 is energized in the normal direction. The circuit for supplying energy to winding 17 of lower unit L of signal 12 may be traced over a path which passes from terminal B at signal 13 through front contact 62 of relay 13LOP, contacts 18-21 and 19-22 of lower unit L of signal 13, front point of contact 63 of relay 13LPC, front contact 64 of relay 4TR, front contact 65 of relay 3TR, front contact 66 of relay 12HP, back contact 67 of relay 12DP, front point 70 75 of contact 68 of relay 12LOP, winding 17, front

point of contact 69 of relay 12LOP, front contact 70 of relay 3TR, front contact 71 of relay 4TR, and front point of contact 72 of relay 13LPC to terminal C.

The normal energization of winding 17 of lower unit U of signal 12 establishes a circuit for relay 12UPC which circuit may be traced from terminal B through front contact 73 of relay 12LOP, contact 18-20 of lower unit L of signal 12, and relay 12PC to terminal C. When relay 12PC is 10 energized, the winding 17 of upper unit U of signal 11 is energized in the normal direction by a circuit which passes over a path from terminal B at signal 12 through winding of relay 12ER, front point of contact 74 of relay 12UPC, front contact 75 of relay 2TR, front contact 76 of relay 1TR, front point of contact 77 of relay 11LOP, winding 17, front point of contact 78 of relay 11LOP, front contact 79 of relay 1TR, front contact 80 of relay 2TR, and front point of contact 81 of relay 12UPC to terminal C.

Signal 11 being in the "proceed" position, relay 11DP is energized over contact 18-20 of upper unit U of that signal. The energization of relay 11DP opens its back contact 82 so that 25 winding 17 of lower unit L of signal 11 is deenergized even though the lower line conductors are supplied with energy at signal 12. With the apparatus at signal 11 in this condition, relay 11UPC is energized over a circuit which passes 30 from terminal B through front contact 83 of relay 11LOP, contacts 18-21 and 19-23 of lower unit L of signal 11, front contact 84 of relay 11DP, and relay 11UPC to terminal C. The energization of relay 11UPC maintains the energization 35 in the normal direction of the upper line conductors for the section in rear of location V so that the signal (not shown) for that section is also in condition to display the proceed indication.

The relays UPC are provided with a slow release 40 characteristic so that tumble-down of the signal circuits to the rear will be avoided when the relays PC are transferred from one control circuit to another. For example, when the train K departs from the section immediately to the right 45 of signal 15 so that signal 12 will be caused to assume a condition for the display of the normal proceed indication, the circuit for relay 12UPC will be momentarily opened while contacts 18 and 19 of lower unit L of signal 12 are changing 50 their positions. Due to the slow releasing characteristic of relay 12UPC, however, front points of contacts 74 and 81 of relay 12UPC will not become opened to disturb the energization of the upper line circuit to the rear.

Having thus described the operation of the 55 signaling system, I shall now describe the light-out protection afforded by the apparatus embodying my invention.

For example, with all apparatus in the condition shown in the drawings, I shall assume that either filament 26 or filament 28 of the lamps UE and LE, respectively, of signal 14 becomes broken so that relay 14LOP becomes released. When relay 14LOP is released, the opening of its front contact 50 will disconnect energy from the lower line conductors for section X-Y so that signal 13 will be caused to assume a condition for the display of the "approach" indication. When signal 13 assumes this condition, signal 12 will be 60 caused to assume the condition for the display of the "approach medium" indication and signal 11 will be caused to assume the condition for the display of the "approach intermediate" indication. Consequently, the open filament of either 65 70 75

- lamp UE or LE, when such filaments are dark, will cause the next three successive signals in the rear to display more restrictive indications than they would ordinarily display. An engineer 5 man approaching signal 14, therefore, would receive three restrictive indications before reaching signal 14 so that he would have ample time to prepare to stop at the signal having the defective lamp.
- 10 The deenergization of relay 14LOP would also connect, through rectifier 14Q, windings 17 of both upper and lower units of signal 14 to the lower line conductors for section Y-Z. Since, however, these conductors are carrying no energy 15 due to the presence of the train K in the section to the right of location Z, both windings 17 would become deenergized to cause signal 14 to assume the stop condition. Another train approaching signal 14 would, therefore, receive an indication 20 comprising a single red light.
- If one of the filaments of either the lamp UE or LE at either signal 11, 12, or 13 becomes opened, three successive signals to the rear would be caused to display more restrictive indications in 25 a manner similar to that described in connection with signal 14 and the signal at which the lamp became opened would be caused to assume a condition for the display of a single yellow light. For example, if filament 26 of lamp UE at signal 30 12 becomes opened, then relay 12LOP would become released. The releasing of relay 12LOP would disconnect windings 17 of both upper and lower units of signal 12 from their usual control circuits and would connect both windings 17 35 through other circuits including rectifier 12Q to the lower line conductors for section W-X. Although the line conductors are supplied with energy in the normal direction, the rectifier 12Q is so poled that the energy supplied to windings 40 17 is in the reverse direction. The circuit for winding 17 of upper unit U of signal 12 passes from the output terminals of rectifier 12Q through back points of contacts 85 and 86 of relay 12LOP and the circuit for winding 17 of lower unit L of 45 signal 12 passes from the output terminals of rectifier 12Q through back points of contacts 68 and 69 of relay 12LOP. Signal 12, therefore, would be in condition to display a single yellow light to an approaching train. It is understood 50 that the same operation would take place if the filament 28 of the lower lamp LE should become opened instead of the filament 26 of lamp UE. Also, each of the signals 13 and 11 and associated apparatus would function in a similar manner if 55 the filament of either lamp associated therewith became opened. For example, if filament 26 of lamp UE of signal 11 becomes opened so that relay 11LOP becomes released, then winding 17 of lower unit L of signal 12 would become energized 60 in the reverse direction by a circuit which passes from the output terminals of rectifier 11Q through back points of contacts 94 and 95 of relay 11LOP. The circuit for supplying energy to rectifier 11Q passes from terminal B at signal 12 through front 65 contact 73 of relay 12LOP, front contact 87 of relay 12HP, back point of contact 88 of relay 12LPC, front contact 89 of relay 2TR, front contact 90 of relay 1TR, rectifier 11Q, front contact 91 of relay 1TR, front contact 92 of relay 2TR, 70 and back point of contact 93 of relay 12LPC to terminal C. When winding 17 of unit L of signal 11 is energized in the reverse direction, that signal, of course, is in condition to display a single yellow light when relay 11ER becomes released by 75 an approaching train.

It will be noted that the lower line conductors for the section immediately in the rear of location V are supplied with energy over a circuit which includes front contact 83 of relay 11LOP and front contact 96 of relay 11DP. This is done to provide energy for the control of the indication units associated with the signal for such rear section (in a manner similar to that described for signal 11) if the filament of one of the lamps of such rear signal should become 10 opened.

Referring next to Fig. 2, I have illustrated herein a single signal and associated apparatus, a plurality of which when connected in a signaling system, will provide four-block, five-indication signaling similar to that just described for the apparatus shown in Figs. 1A, 1B, and 1C. That is, if a plurality of signals and associated apparatus similar to that shown in Fig. 2 are embodied in a system with wires 100, 101, 102, 20 and 103 at the left of Fig. 2 connected to wires 104, 105, 106, and 107 at the right of Fig. 2, the system formed thereby will provide four-block, five-indication signaling. The principal difference between the arrangement shown in Fig. 2 25 and that shown in the preceding figures is that the normal proceed indication is a green light over a green light and the approach intermediate indication is a green over a yellow light. Otherwise, the apparatus shown in Fig. 2 functions in 30 a manner similar to that described for the apparatus shown in Figs. 1A, 1B, and 1C.

If either filament 26 or 28 of lamp US or LE, respectively, becomes opened, relay LOP, of course, will be released. The opening of front contact 108 of relay LOP will release relay UPC so that current will be supplied in the reverse direction to wires 100 and 101 and will disconnect energy from wires 102 and 103. Therefore, if either filament becomes opened, the signal (not shown) for the section next in rear will be caused to assume the condition for the display of a yellow over a red light to indicate "approach medium."

Also the opening of front points of contacts 110, 111, 112, and 113 of relay LOP and the closing of back points of these contacts will connect windings 17 of both upper and lower units U and L to line conductors 106 and 107 through rectifier Q so that both windings will be energized in the reverse direction. The signal, therefore, will be in condition to display a single yellow light to an approaching train regardless of which lamp of the signal is opened.

From the foregoing description of each of the 55 forms of apparatus embodying my invention, it will be seen that I have shown and described herein, lightout protection schemes as applied to four-block, five-indication signaling systems wherein if a lamp filament becomes opened, the 60 next three signals in the rear will be caused to assume a condition, if not already in such condition, for the display of a restrictive indication, and wherein the signal at which the lamp became opened will be caused to assume a condition 65 for the display of a single yellow light or a single red light depending upon traffic conditions in advance.

Although I have herein shown and described 70 only two forms of apparatus embodying my invention, it is understood that various changes and modifications may be made therein within the scope of the appended claims without departing from the spirit and scope of my invention. 75

Having thus described my invention, what I claim is:

1. In combination, a section of railway track, a signal for said section including two indication units, said units each comprising a mechanism and a lamp cooperating therewith to provide a plurality of indications, means for lighting both lamps to cause the display of an indication, means governing said two mechanisms in such a manner that the signal is caused to assume a condition for displaying the "stop", "approach", "approach medium", "approach intermediate", or "proceed" indication in accordance with traffic conditions in advance of the signal, and means effective if the filament of either lamp becomes opened at any time to condition said mechanism for the display of one or another of two distinctive aspects according as the governing means for said signal is then in condition to cause the signal to display the first two or the last three of said indications respectively.

2. In combination, a section of railway track, a signal for said section including two indication units, said units each comprising a mechanism and a lamp cooperating therewith to provide a plurality of indications, means for lighting both lamps to cause the display of an indication, means governing said two mechanisms in such a manner that the signal is caused to assume a condition for displaying a stop indication or a proceed indication in accordance with traffic conditions in advance of said signal, and means effective if the filament of either lamp becomes opened at any time to condition said signal for the display of one or another of two distinctive aspects according as the governing means for said signal is then in condition to cause the signal to display the stop or the proceed indication respectively.

3. In combination, a section of railway track, a signal for said section including two indication units, said units each comprising a mechanism and a lamp cooperating therewith to provide a plurality of indications, means for lighting both lamps to cause the display of an indication, means governing said two mechanisms in such a manner that the signal is caused to assume a condition for displaying a more restrictive indication or a less restrictive indication in accordance with traffic conditions in advance of said signal, and means effective if the filament of either lamp becomes opened at any time to condition said signal for the display of one or another of two distinctive aspects according as the governing means for said signal is then in condition to cause the signal to display the more restrictive or the less restrictive indication respectively.

4. In combination, a section of railway track, a signal for said section including two indication units, said units each comprising a mechanism and a lamp cooperating therewith to provide a plurality of indications, means for lighting both lamps to cause the display of an indication, means governing said two mechanisms in such a manner that the signal is caused to assume a condition for displaying a more restrictive indication or a less restrictive indication in accordance with traffic conditions in advance of said signal, and means effective if the filament of either lamp becomes opened at any time to condition said signal for the display of one or the other of two distinctive aspects according as the governing means for said signal is then in condition to cause the signal to display the more restrictive or the less restrictive indication respectively, said two distinctive as-

pects being also more and less restrictive respectively.

5. In combination, a section of railway track, a signal for said section including two indication units, each said unit comprising a mechanism and a lamp cooperating therewith to provide a plurality of indications, means for lighting both lamps to cause said signal to display an indication, a relay, means for energizing said relay at all times provided the filament of each lamp is intact, and means including said relay and operative on deenergization of said relay for controlling said two mechanisms in accordance with traffic conditions in advance of said signal.

6. In combination, a section of railway track, a signal for said section including two indication units, each said unit comprising a mechanism and a lamp cooperating therewith to provide a plurality of indications, means for at times supplying current to the filaments of said lamps to thereby light both lamps to cause said signal to display an indication, a relay, means for energizing said relay provided the filament of each lamp is intact, the means for energizing said relay being rendered ineffective immediately upon failure of the filament of either lamp either at a time when the lamps are supplied with current or when they are not supplied with current, whereby the relay becomes released at once on failure of the filament of either lamp, a circuit including a front contact of said relay for governing one of said mechanisms, and a circuit also including a front contact of said relay for governing the other mechanism.

7. In combination, a section of railway track, a signal for said section including two indication units, each said unit comprising a mechanism and a lamp cooperating therewith to provide a plurality of indications, means for lighting both lamps to cause said signal to display an indication, a relay, means for energizing said relay at all times provided the filament of each lamp is intact, means effective when said relay is energized to govern both said mechanisms in accordance with traffic conditions in advance, and other means effective when said relay is deenergized to also govern said mechanisms in accordance with traffic conditions in advance.

8. In combination, a section of railway track, a signal for said section including two indication units, each said unit comprising a mechanism and a lamp cooperating therewith to provide a plurality of indications, means comprising circuits for supplying current for lighting both lamps to cause said signal to display an indication, a first lightout relay connected in series with one of said lamps when the circuit associated therewith is conditioned to supply current to that lamp, a second lightout relay connected in series with the other of said lamps when the circuit associated therewith is conditioned to supply current to that lamp, an auxiliary relay, a circuit for said auxiliary relay including the filaments of both lamps in series and a back contact of each of said lightout relays when the lamps are extinguished, another circuit for said auxiliary relay including a front contact of each of said lightout relays, and means governed by said auxiliary relay for governing said two mechanisms.

9. In combination, a section of railway track, a signal for said section including two indication units, each such unit including a mechanism responsive to the polarity of the current supplied thereto and a lamp cooperating therewith to

- provide a plurality of indications, means for supplying each mechanism with current in one direction or the other in accordance with traffic conditions in advance of said section, means for lighting both lamps to cause the signal to display an indication, and means effective if the filament of either lamp becomes opened at any time to cause both mechanisms to assume the same condition, the condition which the said mechanisms are caused to assume being controlled in accordance with traffic conditions in advance.
10. In combination, a section of railway track, a signal for said section including two indication units, each such unit comprising a mechanism responsive to the polarity of the current supplied thereto and a lamp cooperating therewith to provide a plurality of indications, means for lighting both lamps to cause the signal to display an indication, a pair of line conductors for supplying energy to one of said units, another pair of line conductors for supplying energy to the other of said units, pole changing means for reversibly supplying energy to each pair of conductors in accordance with traffic conditions in advance of said section, and means effective if the filament of the lamp associated with either unit is broken to render said pole changing means ineffective and to cause each mechanism to assume the same condition.
11. In combination, a section of railway track, a signal for said section including two indication units, each such unit comprising a mechanism responsive to the polarity of the current supplied thereto and a lamp cooperating therewith to provide a plurality of indications, means for lighting both lamps to cause the signal to display an indication, a relay, means for energizing said relay only if the filament of each lamp is intact at all times, means including a pair of line conductors for reversibly governing one of said mechanisms, means including another pair of line conductors for reversibly governing the other of said mechanisms, means including front contacts of said relay for at times connecting each mechanism to its line conductors, and means including a rectifier and back contacts of said relay for at other times connecting both units to one of said pair of conductors.
12. In combination, a section of railway track, a signal for said section including two indication units, each such unit comprising a mechanism responsive to the polarity of the current supplied thereto and a lamp cooperating therewith to provide a plurality of indications, means for lighting both lamps to cause the signal to display an indication, a relay, means for energizing said relay effective only if the filament of each lamp is intact while extinguished as well as while burning, means including a pair of line conductors for reversibly governing one of said mechanisms provided said relay is energized, means including another pair of line conductors for reversibly governing the other of said mechanisms provided said relay is energized, a rectifier having its input terminals connected across one pair of said conductors, means including a pair of back contacts of said relay for connecting the output terminals of said rectifier to one of said mechanisms, and means including another pair of back contacts of said relay for also connecting the output terminals of said rectifier to the other mechanism.
13. In combination, a plurality of successive sections of railway track, a signal for each section including two indication units, each said unit comprising a mechanism responsive to the polarity of the current supplied thereto and a lamp cooperating therewith to provide a plurality of indications, means for each section for lighting both lamps of the associated signal to 75
- to the polarity of the current supplied thereto and a lamp cooperating therewith to provide a plurality of indications, means for at times supplying current to the filaments of said lamps to thereby light said lamps, two pairs of conductors for each section, one pair for supplying current to one mechanism of the associated signal and the other pair for supplying current to the other mechanism of the associated signal, a relay for each section, means for energizing said relay effective only if the filament of each lamp of the associated signal is intact, the means for energizing said relay being rendered ineffective immediately upon failure of the filament of either lamp either at a time when the lamps are supplied with current or when they are not supplied with current, whereby the relay becomes released at once on failure of the filament of either lamp, means including said relay for connecting said mechanisms to the associated pair of conductors, and pole changing means for each section governed by the associated relay and by the mechanism of the associated signal for governing the supply of current to the conductors for the section next in rear.
14. In combination, a plurality of successive sections of railway track each provided with a track circuit including a track relay, a signal for each section including two indication units, each said unit comprising a mechanism responsive to the polarity of the current supplied thereto and a lamp cooperating therewith to provide a plurality of indications, means for each section for lighting both lamps of the associated signal to cause such signal to display an indication, four conductors for each section governed by the associated track relay, one pair for supplying current to one mechanism of the associated signal and the other pair for supplying current to the other mechanism of the associated signal, and means for each section governed by both of the mechanisms associated with the signal for such section for reversibly supplying current to at least one pair of line conductors for the section next in rear.
15. In combination, a plurality of successive sections of railway track each provided with a track circuit including a track relay, a signal for each section including two indication units, each said unit comprising a mechanism responsive to the polarity of the current supplied thereto and a lamp cooperating therewith to provide a plurality of indications, means for each section for lighting both lamps of the associated signal to cause such signal to display an indication, four conductors for each section governed by the associated track relay, one pair for supplying current to one mechanism of the associated signal and the other pair for supplying current to the other mechanism of the associated signal, and means for each section governed by both of the mechanisms associated with the signal for such section for reversibly supplying current to at least one pair of line conductors for the section next in rear.
16. In combination, a plurality of successive sections of railway track, a signal for each section including two indication units, each said unit comprising a mechanism responsive to the polarity of the current supplied thereto and a lamp cooperating therewith to provide a plurality of indications, means for each section for lighting both lamps of the associated signal to 75

cause that signal to display an indication, means for each section for reversibly governing the mechanisms of the associated signal in accordance with traffic conditions in advance, and means for each section effective if the filament of either lamp of the associated signal becomes opened at any time to condition both mechanisms of the associated signal for the display of the same restrictive indication, the condition which 10 the said mechanisms are caused to assume being controlled in accordance with traffic conditions in advance.

17. In combination, a stretch of railway track divided into a plurality of successive block sections, a signal for each section including two indication units, each of said units comprising a lamp and a mechanism associated therewith, each of said mechanisms being movable to a plurality of positions to provide a plurality of indications, means for lighting both of said lamps, circuits controlled by the mechanisms associated with each signal in accordance with their position for selectively controlling the mechanisms of the adjacent signal in the rear, a relay associated with each signal and controlling the connection of the mechanisms at such signal with the circuits leading from the adjacent signal in advance, said relay being operative when de-energized to effect the connection of the associated mechanisms with said circuits to cause said mechanisms to be controlled in one manner in accordance with the positions of the mechanisms of the adjacent signal in advance, said relay being operative when deenergized to effect the connection of the associated mechanisms with said circuits to cause said mechanisms to be controlled in a different manner in accordance with the positions of the mechanisms of the adjacent signal in advance, and means for energizing said relay at all times provided the filament of each lamp at said signal is intact.

18. In combination, a stretch of railway track divided into a plurality of successive block sections, a signal for each section including two indication units, each of said units comprising a lamp and a mechanism associated therewith, said mechanism being movable to a plurality of positions to provide a plurality of indications, a supply circuit through which current may be supplied to the filaments of said lamps in parallel to light said lamps, a relay, means controlled by said relay and operative when said relay is energized for controlling said two mechanisms in accordance with traffic conditions in advance of said signal, means for supplying current to said supply circuit and for also interrupting the supply of current to said circuit, said means being operative when conditioned to interrupt the supply of current to said supply circuit to establish a circuit including the filaments of said lamps in series through which current may be supplied to said relay, and means operative on the supply of current to said supply circuit for also supplying current to said relay.

19. In combination, a stretch of railway track divided into a plurality of successive block sections, a signal for each section, each of said sections having two pairs of line conductors associated therewith and extending to the adjacent signal in advance, the signal for each section including two indication units, each of said units comprising a lamp and a mechanism associated therewith, said mechanism being movable to a plurality of positions in accordance with the polarity of current supplied thereto to provide a plu-

rality of indications, means for lighting both of said lamps, circuits controlled by the mechanisms associated with each signal in accordance with their positions for selectively controlling the supply of current and the polarity of the current supplied to the line conductors associated with the adjacent signal in the rear, a relay associated with each signal and controlling the connection of the mechanisms at such signal with the line conductors extending from the adjacent signal in advance, an asymmetric unit associated with said relay and being operative to supply current of one polarity from one of said pair of line conductors when said line conductors are energized, said relay being operative when de-energized to establish connection from said asymmetric unit to the mechanism of one of said units, and means for energizing said relay at all times provided the filament of each lamp remains intact.

20. In combination, a stretch of railway track divided into a plurality of successive block sections, a signal for each section, each of said sections having two pairs of line conductors associated therewith and extending to the adjacent signal in advance, the signal for each section including two indication units, each of said units comprising a lamp and a mechanism associated therewith, said mechanism being movable to a plurality of positions in accordance with the polarity of current supplied thereto to provide a plurality of indications, means for lighting both of said lamps, circuits controlled by the mechanisms associated with each signal in accordance with their positions for selectively controlling the supply of current and the polarity of the current supplied to the line conductors associated with the adjacent signal in the rear, a relay associated with each signal and controlling the connection of the mechanisms at such signal with the line conductors extending from the adjacent signal in advance, an asymmetric unit associated with said relay and being operative to supply current of one polarity from one of said pair of line conductors when said line conductors are energized, said relay being operative when de-energized to establish connection from said asymmetric unit to the mechanisms of both of said units, and means for energizing said relay at all times provided the filament of each lamp remains intact.

21. In combination, a section of railway track divided into a plurality of successive block sections, a signal for each section including two indication units, each of said units comprising a mechanism and a lamp cooperating therewith to provide a plurality of indications, each signal having associated therewith means for at times supplying current to the filaments of said lamps to thereby light both lamps to cause said signal to display an indication, each signal also having associated therewith a relay, a circuit for energizing said relay at a time when current is not supplied to illuminate the filaments of the said lamps, another circuit for energizing said relay at a time when current is supplied to illuminate the filaments of the said lamps, said circuits being effective to energize said relay only if the filaments of both lamps are intact, and means including said relay and operative on deenergization of said relay for controlling the mechanisms of the associated signal in accordance with traffic conditions in advance of the section with which the signal is associated.

CERTIFICATE OF CORRECTION.

Patent No. 2,155,870.

April 25, 1939.

GEORGE R. PFLASTERER.

It is hereby certified that error appears in the printed specification of the above numbered patent requiring correction as follows: Page 7, first column, line 28-29, claim 17, for the word "deenergized" read energized; and that the said Letters Patent should be read with this correction therein that the same may conform to the record of the case in the Patent Office.

Signed and sealed this 11th day of July, A. D. 1939.

(Seal)

Henry Van Arsdale
Acting Commissioner of Patents.
